ELECTRICALLY HEATED TOOL

Leon N. Hampton, New York, N. Y., assignor to
 Bell Telephone Laboratories, Incorporated, New
 York, N. Y., a corporation of New York

Application August 5, 1931, Serial No. 555,174

6 Claims. (Cl. 219—26)

This invention relates to electrically heated tools and more specifically to that class of tools known as electric soldering coppers.

The object of this invention is to improve the construction and efficiency of such tools.

The features and advantages of this tool will appear from the following description and by the claims appended thereto, reference being made to the accompanying drawing in which:

10 Fig. 1 is an assembly view of the soldering copper shown partly in section;

Fig. 2 is an enlarged longitudinal sectional view of the heating element embodied in this soldering copper;

15 Fig. 3 is an enlarged longitudinal view of the handle showing the switching mechanism;

Fig. 4 is a sectional view taken approximately on line 4—4 of Fig. 3;

20 Fig. 5 is a sectional view taken approximately on line 5—5 of Fig. 3; and

Fig. 6 is a detail view of the switch operating knob.

As shown in Fig. 1 the heat applying member is made of bimetal consisting of a copper portion 25 11 and a silver portion 12, the silver portion having a chamfered edge 13 and a threaded portion 14 for engagement with a similarly threaded bushing 15 having a beveled seat for receiving the chamfered edge of the silver portion 12.

30 Bushing 15 like the portion 12 of the heat applying member is made of silver or any other metal having a similarly high thermal conductivity and non-corrosive characteristic in order to form a good heat path toward the copper portion of the heat applying tip and to prevent the so-called 35 freezing of these parts as it frequently occurs in ordinary soldering copper due to oxidation, and therefore avoiding the liability of damaging these parts upon the removal of the soldering tip from the bushing while at the same time improving the efficiency of the device.

Bushing 15 is secured at its front end in an enlarged portion of a supporting shell 16 made of non-corrosive material such as for example an 45 alloy of chromium metal steel commercially known as "Enduros". This bushing is held in the shell by a number of rivets 17 and for a distance of about two-thirds of its length cooperates with the shell 16 to form an annular air space 18 for thermally insulating the supporting shell 16 50 and preventing the dissipation of the heat to the atmosphere from the bushing 15, thus forcing the heat toward the heat applying member or tip 11.

In the bushing 15 there is mounted a heating element HE shown in Figs. 1 and 2. This element

consists of a core 19 of a non-oxidizable material such as "Monel" metal which is highly efficient thermally as compared to "Lavite" and other insulating material heretofore used and does not corrode and scale at soldering temperature. This core is coated with an insulating oxide at a temperature of about 2000° F. and around the core 19 is wrapped a strip of insulating material 20 such as mica on which the nichrome resistance wire 21 is coiled in a non-inductive manner. The loop 10 end of the resistance wire 21 engages a lug 22 formed at the periphery of a ring 23 of lavite material mounted on the front end of the core, the ends of the nichrome wire at the other end being inserted in slots in the periphery of a lavite bead 24.

To the front end of the core 19 there is welded a silver bushing or cap 25 having a flange portion 26 for engaging the core. A shoulder portion 27 is provided in the cap 25 for receiving the end of 20 a sleeve 28 also made of silver and this sleeve is welded to the cap 25.

The sleeve 28 is thermally and electrically insulated from the resistance wire 21 by an annular layer 29 of insulating material as for example, 25 magnesium oxide. The ends of wire 21 thread through metallic sleeves 30 and 31 supported by a plurality of mica washers 32, and a lavite bead 33 in turn mounted in the sleeve 28 and a packing 34 of magnesium oxide is placed between 30 the bead 24 and the mica washer 32 as shown in Fig. 2.

The end of sleeve 28 adjacent the bead 33 is then spun over the edge of this bead in order to form a self-contained unit and the diameter 35 of the sleeve 28 is then reduced, as by swaging, in order to obtain a dense insulating coating around the resistance wire and at the same time denuding the magnesium oxide of gaseous substance to prevent the oxidation and the consequent burning of the resistance wire. The annular air space formed by the reduced portion of sleeve 28 with the bushing 15 further assists in the heat insulation of the supporting shell 16.

On the protruding ends of bushings 30 and 31 45 there is mounted an insulating bead 34 of Lavite provided for holding the wires 35 and 36 in co-axial alignment with the ends of the resistance wire 21 with which these wires connect as shown in Fig. 2.

The supporting shell 16 has a reduced portion 50 in which is mounted a series of ceramic beads such as 37. These beads are of a diameter as to form with the inner diameter of the shell an annular air space and are provided with radial fins 55

38. The reduced portion of shell 16 is provided with a series of holes 39 to permit the dissipation of any heat which may reach these beads and this portion of the shell, thus forming an air 5 path from the open ends of the annular spaces formed by the sleeve portion of bushing 15 with the heating element and the supporting shell 18.

The supporting shell 16 is provided with a double convex collar portion 40, one face of which 10 is provided with radial grooves 41 for assisting in the dissipation of the heat from the shell, and the other face is provided with two parallel flat portions 42 and 43 to be engaged by a wrench in the ordinary manner for securing the shell in 15 a handle 44 through the engagement of the threaded portion 45 at the end of the shell 16 with a similarly threaded metal insert 46 anchored in the handle 44, the grooved face of the double convex member 40 serving as a stop 20 against the front end of the metal insert 46.

The wires 35 and 36 thread through parallel holes 47, Fig. 2, in the ceramic beads 37 and are connected to terminals 48 and 49 secured to a mounting block 50 of insulating material by a 25 screw 51 and a stud 52 the latter being placed at the center of the block 50.

A slip ring 53 is held in place on the other face of this block by a screw 54 and the screw 51, the latter electrically connecting terminal 48 with 30 the slip ring 53. The stud 52 is mounted on an insulating washer 55 also secured to the block 50 by the screws 51 and 54. The insulating block 50 is provided with a counter-sunk hole 56 in which is mounted a contact member 57. This 35 contact is held in contacting relation with a co-axially disposed contact 58 by a spring 59. Contact 58 is anchored in a mounting block 60 of insulating material and in this block is anchored a contact member 61 disposed in contact relation 40 with the slip ring 53 and to each of the contacting members 58 and 61 is secured one end of wires 62 and 63 by screws 64 and 65 respectively.

The insulating block 60 which is made preferably of molded phenol plastic composition material is formed with a hook portion 66 for engaging a similarly shaped portion 67 in a plate 68 which is fastened to a frame 69 of a switching device SD by lugs 70 and 71 riveted to this 45 frame. On this plate is insulatively mounted two switch blades 72 and 73. To blade 73 is attached the other end of wire 63 and to blade 72 is attached one end of wire 74 of the current supply 50 circuit, the wire 62 of the supply circuit being connected directly to the contact member 58 as 55 above described.

On frame 69 is pivotally mounted a lever member 75 which carries at its free end a substantially U-shaped contacting member 76 arranged 60 to engage the switch blades 72 and 73 and thereby establishing electrical connection between the wires 63 and 74.

Lever member 75 is actuated by a sector-shaped piece 77 shown in Figs. 1, 3, 5 and 6 pivoted as at 78 in the frame 69. The movement of sector 77 and the arm 79 carried thereby is effective to tension a spring 80 while moving one of its ends past the pivotal point of lever 75 where the spring 80 is caused to detent and move 70 the bridge piece 76 in contacting relation with the blades 72 and 73.

The frame 69 is provided at its free end with a lug portion 81 arranged for engaging a recess or groove in the handle 44 as shown in Figs. 3 and 75 4 and at the rear end of this frame are formed

two lugs 82 and 83 supported by an insulation block 84. The block 84 fits the inner diameter of the handle 44 and is provided with peripheral grooves 85 and 86 for holding the wires 62 and 74 in spaced relation at that point. A spring 87 5 which has one end in abutment against the block 84 and the other end against the end piece 88 of handle 44 is provided for holding the frame 69 against axial movement in the handle.

The electrical circuit for the heating element 10 is as follows. From the supply wire 62, the screw 64, the contact member 58 engaging the plunger 57, the spring 59, the stud 52, terminal 49 and the wire 36 which connects with one end of the resistance wire 21. The return side of the circuit 15 is through the wire 35, terminal 48, the screw 51, the slip ring 53, the contact member 61, the attaching screw 65, the wire 63 attached to switch blade 73, the bridge piece 76 in the closed position, the switch blade 72 and the supply wire 74, 20 such circuit being opened upon the disengagement of the bridge piece 76 from the switch blades 72 and 73 through the operation of the actuating sector member as above described. On the operating knob 77 is provided a reference 25 point 88' of a color different from that of the body portion of the knob for visually indicating the closed and open position of the knob.

The comparatively high degree of efficiency obtained in the electric soldering copper of this 30 invention is due in part to the use of semi-precious metal for a number of parts of the heating element including a portion of the soldering tip, and through the proper thermal and electrical insulation of the parts. Due to the high efficiency 35 obtained, it has been found that the heating element may be operated at a lower temperature than is practiced in ordinary soldering copper at present in the market, which results in longer life of the heating element, and in the 40 retardation of the deterioration rate of the instrument. Further, it has been found that the soldering tip becomes hotter in relation to the shell than otherwise would be the case and that the supporting shell and the handle are cooler 45 in proportion. The hotter tip is desirable from a soldering standpoint. The cooler shell offers greater protection against searing or scorching of adjacent material during soldering and the cooler handle makes the copper more comfortable 50 able to handle and prolongs the life of the handle.

The use of semi-precious metal in the heating element and soldering tip also prevents scaling and oxidation of the parts and therefore prevents the gradual falling off in efficiency with the attendant increase in the temperature of the shell and in the handle and the so-called freezing of the soldering tip with its supporting bushing at the screw threads of these parts thus 60 avoiding the liability of damaging these parts upon the removal of the soldering tip from the bushing.

A switch which is placed in the handle affords a convenient means for controlling the operation 65 of the heating element, while its operating knob, which protrudes only slightly above the surface of the handle, does not interfere in any way with the practical handling of the instrument.

What is claimed is:

1. In an electric soldering tool, a bimetallic heat applying means consisting of copper and silver, the silver part having a threaded portion, a supporting shell, a silver bushing mounted in 75

5 said shell for receiving said threaded portion and a heating element for said means mounted in said bushing, said bushing extending over the whole length of said heating element, said bushing and said heating element having portions of their outer diameters reduced to form a plurality of concentric air spaces for heat insulating said shell from said element.

10 2. In an electrically heated tool, the combination with a heat applying means and a tubular support, a heating element for said means, a bushing mounted in said support for engaging said means, and having a portion extending over said heating element in spaced concentric relation therewith, said element comprising a core, a strip of insulating material wrapped around said core, a resistance wire coiled around said insulation, a metallic protective shell, magnesium oxide interposed between said shell, said 15 wire and a plurality of means at each end of said shell for insulatively supporting said core and a metallic cap secured to the front end of said metallic shell and forming an abutting wall for the last mentioned means.

20 25 3. An electrically heated tool comprising a tubular support, a heating element mounted in one end of said support, a handle mounted at the other end of said support, a switching device in said handle for controlling the operation of said element, a pair of wires in said support connected at one end to said element, an insulating block mounted in said tubular support, having contacts connected to the other ends of said wires, another insulating block in said support 30 carried by said switch and having contacts engaging the contacts in the first mentioned block and current supply circuit wires connected to said switching device and the last mentioned block.

35 40 4. An electric soldering tool comprising a supporting shell, a bushing mounted in one end of said shell, a bimetallic heat applying means consisting of a copper part and a silver part, the silver part having a screw threaded portion engaging said bushing, a heating element for said means mounted in said bushing, said element having its middle portion reduced in diameter to form with the inner diameter of said bushing an annular air space open at one end, the outer 45 diameter of said bushing being reduced at one

end to form with said supporting shell another air space open at one end, air openings in said shell connecting said air spaces with the atmosphere for cooling said shell and a handle secured at the other end of said shell.

5 10 15 5. In an electric soldering tool, a supporting shell, a bimetallic heat applying means, one part of said means being silver and the other part copper secured to each other, a silver bushing having a threaded portion and a sleeve portion, the silver part of said means having portions interfitting said bushing, a heating element for said means mounted in said sleeve portion, said sleeve portion extending in concentric and spaced relation with said shell and said element 20 to form therewith a plurality of air spaces for heat insulating said shell from said element, a handle at the other end of said shell, a switching device in said handle for controlling the operation of said heating element and insulating 25 plugs in said supporting shell, one carried by said switching device and having engageable contacts connecting said switching device to said heating element.

25 30 35 40 45 50 6. An electrically heated tool comprising a tubular support, a bushing having a reduced sleeve portion mounted in one end of said support, the sleeve portion forming an annular air space open at one end thereof, a heat applying means engaging said bushing, a heating element mounted in the sleeve portion of said bushing in end-to-end abutting relation with said heat applying means, a cone portion carried by said support, a handle mounted on the other end of said support in abutting relation with said cone portion, a switching device mounted in said handle, a two-position rotatable sector member protruding at one point from said handle for operating said device, electrical connections in said support extending from said device to said element, said connections including a pair of detachably mounted plugs having end-to-end engageable contacts, a plurality of means for electrically and thermally insulating said connections from said support, said sector member in one position causing the operation of said element and when rotated in the other position breaking said connections, and means for indicating said positions.
